UNITED STATES PATENT OFFICE.

SALVATORE SANTINO, OF CHICAGO, ILLINOIS, ASSIGNOR TO LOUIS C. BERMAN, OF CHICAGO, ILLINOIS.

JACK.

1,339,583.

Specification of Letters Patent. Patented May 11, 1920.

Application filed September 12, 1919. Serial No. 323,306.

To all whom it may concern:

Be it known that I, SALVATORE SANTINO, a citizen of the United States, and a resident of the city of Chicago, county of Cook, 5 and State of Illinois, have invented certain new and useful Improvements in Jacks, of which the following is a specification.

My invention relates to jacks, and has for one of its objects, the provision of a 10 simple and efficient jack capable of easy and quick operation.

A further object is the provision of a simple and efficient jack adapted for operating step by step both in its lifting and 15 lowering operations.

A still further object is the provision of a jack having quick return means which cannot be operated except when there is no load on the jack.

20 Other objects will appear hereinafter.

An embodiment of my invention is shown in the accompanying drawings forming a part of this specification, and in which,

25 Figure 1 is a side view of a jack embodying my invention,

Fig. 2 is an edge view of the same,

Fig. 3 is a fragmentary view showing a cam-operating lever of the device,

30 Fig. 4 is a vertical section showing the interior parts of the device,

Figs. 5 and 6 are sections taken on lines 5-5 and 6-6, respectively, of Fig. 4, and

Figs. 7, 8 and 9 are fragmentary sections showing the same parts in various positions.

35 Referring more particularly to the drawings, a base 10 is provided with a cross-shaped, in cross section, opening 11 reaching down from its top and in which is disposed the lower end of an upright bar 12.

40 The cross-shaped opening 11 is provided so that the upright bar 12 can be disposed in two positions in the opening 11 at right angles to each other. This arrangement will be useful for many purposes. A pin 13 is inserted through suitable perforations in base 10 for holding the bar 12 in the opening 11 in either of the bar's positions therein. The base 10 is also provided with a horizontal opening 14, see Fig. 4, for the

45 insertion of bar 12 in a horizontal manner, so that the device may be used as a vise or various other purposes which will be apparent to the users thereof.

50 Slidably mounted on the bar 12 is an upper member 15 and a lower member 16.

Each member has an opening substantially fitting the bar 12 so that the members slide easily on the bar without unnecessary play. A lever 17 is pivoted as at 18 to the upper member 15 and connected by a link 19 pivoted as at 20 and 21, see Fig. 1. The lever 17 preferably has one end angular with a short portion thereof extending substantially in alignment with the link 19 when the members 15 and 16 are pressed apart, 60 see Figs. 1 and 4. By providing this arrangement great leverage is given to the lever providing a sort of toggle action between the part of lever 17 between pivots 18 and 20 and the link 19. 65

The lower member 16 is provided with a jaw 22 which has teeth 23 normally engaging the bar 12. On the link 19 is an arm 24 which engages a spring 25. The upper end of the spring bears against a web 26 so as to exert an upward pressure on member 16 75 about the pivot point 21 to press the jaw 22 against the bar 12. 70

The upper member 15 is provided with an inclined surface 27 against which a jaw-holder 28 rests. A compression spring 29 presses against the lower side of jaw-holder 28 and a web 30 so as to exert pressure upwardly on the jaw-holder 28, and due to the inclined surface 27, presses the jaw-holder toward bar 12 so that jaw 31 in said jaw-holder engages the bar 12. With the parts already described, the springs 25 and 29 normally press the jaws 22 and 31 against the bar 12. Upon raising lever 17, see Figs. 90 1 and 4, the link 19 will exert an upward pull on member 16 which tends to rock the latter, moving the jaw 22 away from bar 12 and drawing the member 16 upwardly on said bar toward member 15. When the upper end of link 19 engages a stop 32 on member 15, lever 17 will be limited in its upward movement. Then, upon moving the lever 17 downwardly, jaw 22 will engage bar 12 again and the downward movement 100 of the lever 17 will cause the link and lever to move the member 15 upwardly on bar 12. This upward movement of member 15 will cause jaw-holder 28 to yield downwardly against spring 29 and permit jaw 31 to slide upwardly on bar 12. The downward movement of lever 17 is arrested when the upper end of link 19 engages a stop 33 105 on member 15, see Fig. 4. It will be seen that lifting movement of the jack is auto-

110

matic upon operating lever 17 without the manipulation of any other parts of the jack.

To lower a load with the jack, it is necessary to disengage the jaws 22 and 31 from the bar 12 at proper times. On member 16 is an arm 34 which extends upwardly through an opening 35 into a chamber 36 in member 15. In the member 15 is journaled a shaft 37 which has a plurality of cams 38, 39 and 40 thereon. The shaft 37 is provided with an enlarged part 41 which is journaled in one side of member 15 and provided with a spring washer 42 at its other end bearing on the other side of member 15 to provide a frictional lock for said shaft. The frictional lock is desirable for holding the shaft against the forces which will be placed against the cams 38, 39 and 40 in use.

The cams 38 and 39 are formed on shaft 37 in a position to be rocked against arm 34, and cam 40 is positioned on shaft 37 where it will engage an arm 43 on the lower part of jaw-holder 28. The shaft 37 is provided with a handle 44 by means of which it can be oscillated manually. When the handle 44 is moved manually to the position indicated in Fig. 9, it will be apparent that cam 40 is engaged against arm 43 and cam 38 engaged against arm 34 to move both jaws 22 and 31 from bar 12. In this position the members 15 and 16, and the parts thereon, may be moved up and down the bar 12 freely as desired. It will be noted, however, that if a load is on the jack, it will be impossible to move lever 44 from positions such as indicated in Figs. 4, 7 and 8, because the load would hold one of said jaws so tightly against the bar 12 that lever 44 could not be moved. It is only when no load is on the jack that both jaws 22 and 31 can be moved out of engagement with the bar 12. This prevents a load on the jack from being accidentally dropped.

On one side of arm 34, I provide two shoulders 45 and 46 which are adapted to engage a crank pin 47 which is mounted in lever 44 eccentrically to shaft 37. The pin 47 has a shoulder 48 which is adapted to rest against the outer side of lever 44, see Fig. 3, and is held normally in this position by a flat spring 49. The arrangement is such that when pin 47 is rotated by a hand lever 50, the spring 49 will still rest against the flange or flat part 48. On the under side of the flange 48 is provided a cam 51 which engages a cam surface 52 in lever 44. The arrangement is such that when cam 51 registers with cam surface 52, spring 49 presses the pin 47 into the space between shoulders 45 and 46 should said shoulders be in proper position, and if the shoulders are not in proper position, then pin 47 will rest against the surface 53 or 54 adjacent said shoulders and slide into the space between said shoulders as soon as arm 34 is

moved sufficiently. When, it is desired to move the pin 47 out of engagement with the shoulders 45 and 46, the handle 50 is operated to rotate the pin 47 thereby sliding cam 51 out of engagement with surface 52 and the end of cam 51 will ride on surface 55 on lever 44 to hold the pin 47 away from said shoulders. The pin 47 is held out of the path of said shoulders in using the device for lifting, and in engagement with said shoulders when it is desired to lower a load.

To lower the load, considering the parts 15 and 16 in their relations indicated in Figs. 1 and 4, lever 50 would first be operated to cause pin 47 to move into the paths of shoulders 45 and 46. Then upon upward movement of lever 17, arm 34 will move upwardly with member 16 until the pin 47 moves into the space between shoulders 45 and 46 and engages shoulder 45 to rock shaft 37 and move cam 39 against arm 34 to free jaw 22 from bar 12, see Fig. 8. Upon downward movement of lever 17, the pin 47 will engage shoulder 46 and rock shaft 37, bringing cam 40 against arm 43 and pull the jaw-holder 28 and jaw 31 downwardly to disengage jaw 31 from bar 12, see Fig. 7. It will be apparent that the load will be held by member 16 and jaw 22 while member 15 is being lowered, and that jaw 31 and member 15 will hold the load while member 16 is being lowered.

I claim:

1. A jack comprising a bar; upper and lower members slidably mounted on the bar; a lever pivoted to one member; a link pivoted to the lever and said other member; a jaw in the lower member; a jaw-holder in the upper member; a jaw in the jaw-holder; a shaft in the upper member; cams on said shaft; a pin associated with said shaft; an arm on the lower member having means thereon adapted to engage said pin for oscillating the shaft to move the jaws away from said bar.

2. A jack comprising a bar; upper and lower members slidably mounted on the bar; a lever pivoted to one of the members; a link connecting the other member with said lever; a shaft in the upper member; cams on the shaft; a jaw-holder in the upper member having a portion adapted to engage a cam on said shaft; an arm on the lower member adapted to engage a cam on said shaft; a crank pin on the shaft; and shoulders on the arm adapted to engage the crank pin for oscillating the shaft.

3. A jack comprising a bar; upper and lower members slidably mounted on the bar; a lever pivoted to one of the members; a link connecting the other member with said lever; a shaft in the upper member; cams on the shaft; a jaw-holder in the upper member having a portion adapted to engage

a cam on said shaft; an arm on the lower member adapted to engage a cam on said shaft; a crank pin on the shaft; shoulders on the arm adapted to engage the crank pin 5 for oscillating the shaft; and means for moving the crank pin out of engagement with said shoulders.

4. A jack comprising a bar; upper and lower members slidably mounted on the bar; 10 a lever pivoted to one of the members; a link connecting the other member with said lever; a shaft in the upper member; cams on the shaft; a jaw-holder in the upper member having a portion adapted to engage 15 a cam on said shaft; an arm on the lower member adapted to engage a cam on said shaft; a crank pin on the shaft; shoulders on the arm adapted to engage the crank pin for oscillating the shaft; and stops associated with certain of the movable parts for 20 limiting the movements of said shoulders with respect to the crank pin.

5. A jack comprising a bar; upper and lower members slidably mounted on the bar; 25 a lever pivoted to the upper member; a link connecting the lower member with the lever; stops on the upper member in the path of said link adapted to limit the movements of said members toward and away from each 30 other; a spring-pressed jaw-holder in the upper member; a jaw in the lower member; a jaw in said jaw holder; a spring pressing against the lower member and tending to press the jaw in the latter against the 35 bar; a shaft in the upper member; cams on the shaft; a crank pin on the shaft; an arm on the lower member; and shoulders on the arm adapted upon relative movements of the members to engage said crank pin and 40 oscillate said shaft to engage the cams with the arm and jaw-holder for moving the jaws, one at a time, away from the bar.

6. A jack comprising a bar; upper and lower members slidably mounted on the 45 bar; a lever pivoted to one of said members; a link connecting the other member with said lever; a shaft journaled in the upper member; cams on the shaft; a jaw-holder in the upper member having a portion adapted to engage a cam on said shaft; an arm on the lower member adapted to engage a cam on said shaft; jaws in the lower member and said jaw-holder; and a manually operable lever on said shaft for rotating the latter to bring said cams into engagement with said jaw-holder and arm for moving said jaws away from said bar.

7. A jack comprising a bar; upper and lower members slidably mounted on the 50 bar; a lever pivoted to one of said members; a link connecting the other member with said lever; a shaft journaled in one member; an enlargement on said shaft engaging one side of said member; a spring on the shaft engaging the other side of said member, said

enlargement and spring providing a frictional lock for said shaft; an arm on the other member; a jaw holder in the first-mentioned member; cams on said shaft adapted to engage the arm and jaw-holder; 70 and an operative connection between the arm and shaft.

8. A jack comprising a bar; upper and lower members slidably mounted on the bar; a lever pivoted to one of said members; 75 a link connecting the other member with said lever; a shaft in the upper member frictionally locked against turning; a plurality of cams on said shaft; a jaw-holder in the upper member; jaws in the jaw- 80 holder and lower member; an arm on the lower member; an operative connection between the arm and shaft adapted to rotate the latter and move one of said cams against said arm and another of the cams against the jaw-holder for moving the jaws, one at 85 a time, away from said bar; and a manually operable lever on the shaft adapted to rotate the latter for moving two of said cams against the jaw-holder and arm for 90 moving the jaws, both at once, away from the bar.

9. A jack comprising a bar; upper and lower members slidably mounted on said bar; a lever and a link connecting said slid- 95 able members together; a shaft mounted in one of said members; an arm on the other member; shoulders in said arm; jaws in said members; cams on said shaft; a crank pin mounted on said shaft and extending between said shoulders; and means for moving the crank pin out of engagement with 100 said shoulders.

10. A jack comprising a bar; upper and lower members slidably mounted on said 105 bar; a lever and a link connecting said members together; a shaft mounted in one of said members; an arm on the other member; shoulders on said arm; cams on said shafts; an enlargement on said shaft; a 110 crank pin slidably mounted in said enlargement; a spring engaging said crank pin normally holding a portion of the latter in the path of said shoulders; means associated with the crank pin for moving the latter 115 out of engagement with said shoulders.

11. A jack comprising a bar; upper and lower members slidably mounted on said bar; a lever and a link connecting said members together; a shaft mounted in one 120 of said members; an arm on the other of said members; a jaw holder in the slidable member having said shaft therein; an arm on the said jaw holder; cams on said shaft adapted to engage said arms; and a manually operable lever on said shaft for oscillating the latter to move both of said cams against said arms at the same time.

12. A jack comprising a bar; upper and lower members slidably mounted on said 125

bar; a lever and a link connecting said members together; a shaft mounted in one of said members; an arm on the other of said members; jaws in said members; a spring 5 engaging the member having said arm thereon normally holding the jaw in said member against the bar; a spring pressed jaw holder in the member having said shaft therein and supporting the jaw in said member having the shaft therein; an arm on said 10 jaw holder; cams on said shaft adapted to engage said arms for moving said jaws out

of engagement with said bar; an enlargement on said shaft; means engaging said enlargement for causing friction on the latter; shoulders in the arm on said member; a pin slidably mounted in said enlargement and adapted to engage said shoulders; and means for moving said pin for disengaging the latter from said shoulders. 15 20

In testimony whereof I have signed my name to this specification on this 10th day of September, A. D. 1919.

SALVATORE SANTINO.
